Application April 5, 1941, Serial No. 387,084

29 Claims. (Cl. 66—89)

This invention is concerned with the widening of fabrics during the course of knitting on flat knitted machines through the formation of additional loops at the fabric margins.

The principle of widening fabric through the addition of edge loops, as distinguished from widening by the outward transfer of marginal loops by means of transfer points, has been known in the art for many years and has been recognized as desirable because of the advantages such method offers over the loop transfer method of widening. The logical way of making a single unit full fashioned stocking on one machine is to widen the upper portion of the heel in progressive courses by the addition of edge loops, and thereafter narrow the heel and knit on the foot in a continuous operation so that there will be a continuous selvage edge at the opposite margins of the stocking blank running from top to toe such as can be joined in an uninterrupted seam. It is, of course, a practical prerequisite to widening by the addition of edge loops that locked selvage edges be formed, and this has been difficult to accomplish, especially where two edge loops are to be added at a time in each widening operation. Proposals have been made for securing locked selvage edges, but the practical value thereof has been negligible because they necessitated the use of complicated knitting machine structures which have not received public acceptance. More recent developments, however, have made it possible to widen fabric by the addition of edge loops on conventional type flat knitting machines without the use of special needle co-operating elements, and as a result single unit stockings with widened heels are now being produced commercially on hosiery legger type flat knitting machines.

Experience has shown that the recent developments referred to enable selvage edges to be formed with widening by the addition of edge loops with a fairly high degree of perfection, but sometimes the added loops accidentally are defectively formed and fail to lock with the result that runs are likely to develop. Experience has shown that defects of this nature in the widened fabric are more frequent when the fabric is knit with the same yarn in successive courses than where a series of yarns are used sequentially in respective courses under the so-called "ring-less" system of knitting, and further that more defects are found in the widened fabric when employing Nylon yarn than when employing less resilient and softer silk yarn.

The primary object of the present invention is to provide an improved method of widening by the addition of edge loops adapted to better secure the desired selvage edges along the widened fabric margins. Through the use of the invention it has been found possible to widen fabric of both Nylon and silk, and formed with the same yarn or yarns in successive courses, by two loops at a time with a greater freedom from defects than heretofore possible.

According to the invention auxiliary yarns are introduced into the fabric along the widened marginal areas during the course of knitting additional to the body yarn, and in the case of reinforced fabric additional to the body and splicing yarns. A distinctive feature of the improved process is that the auxiliary yarns are fed from idle carriers which normally stand stationary at the marginal areas of the fabric instead of reciprocating with the yarn carriers which lay their yarns across the needles for the fabric courses. The only time the idle carriers are moved is in connection with the widening steps, and at such times the idle yarn carriers are racked outwardly to lay the auxiliary yarns outwardly across the same number of needles as are to be added in a widening operation so that at such points the auxiliary yarns are interknit in the fabric.

As hereafter pointed out, the auxiliary yarns may be fed into the fabric along the outside edge thereof, or may be fed into the fabric in the marginal area but inside the edge.

While not necessarily confined in its application, the present invention has been found particularly useful as an improvement on the method of widening fabric by the addition of marginal loops forming the subject-matter of B. F. Somers Patent No. 2,230,986, granted February 4, 1941, which is being used commercially to form widened heel sections in single unit stockings on conventional hosiery legger type flat knitting machines. According to such patent selvage edge loops are added to widen the fabric solely through the use of the ordinary knitting instrumentalities (needles, jack and dividing sinkers, knock-over bits and yarn carriers) employed in straight knitting by extending the traverse of the reciprocating yarn carrier or yarn carriers engaged in knitting the fabric while the needles are up in course-laying position incident to the formation of selected courses, laying the following courses without passing the yarn around the outside added needle to form loops around jack or divider sinkers inside the outer added needles,

and when the needles are down for a knockover impaling the sinker-formed loops as selvage loops on the outer added needles. The use of the auxiliary yarns according to the present invention has been found to assist in the formation of selvage loops on the added needles under the Somers method either by assisting in the formation of and tying in with the added loops of course-forming yarn on the added marginal needles, or, according to a modified practice of the invention, by forming loops of the auxiliary yarn on the added needles which aid in the subsequent production of locked loops of course-forming yarn on such needles in the event defective loops of course-forming yarn were formed thereon at the time of the widening operation.

In the knitting of reinforced fabric wherein splicing yarns are employed in conjunction with the main yarn in forming the fabric courses, it is found according to the invention in some cases to be desirable not only to employ the auxiliary yarns in the marginal widened areas but to terminate the traverse of the main yarn and the splicing yarn at different marginal needles so that the marginal widened area will comprise loops of either the body yarn or splicing yarn but not both as will be more fully hereafter explained.

In the accompanying drawings:

Fig. 1 illustrates a full fashioned stocking blank having widened heel portions in connection with which the present invention is useful;

Fig. 2 is a diagrammatic view of a section of fabric widened at recurrent points along the opposite margins and incorporating auxiliary yarns along the outside edges of the marginal areas according to the present invention;

Fig. 3 is a diagrammatic view of a similar section of widened fabric illustrating the incorporation of auxiliary yarns in the marginal areas in a different position from that illustrated in Fig. 2;

Figs. 4a to 4f are diagrammatic views taken from above the needle bank illustrating progressive operating stages in the widening of fabric formed with successive courses of the same yarn by the addition of two loops at the opposite margins, and wherein auxiliary yarns are fed to marginal fabric areas at their outside edges according to one practice of the invention;

Fig. 5 illustrates a section of fabric widened in a plurality of courses at the opposite margins according to the procedure illustrated in Figs. 4a to 4f and showing the manner in which the auxiliary yarns are incorporated in the fabric;

Figs. 6a to 6f are diagrammatic views of successive operating stages in the widening of fabric according to a procedure generally similar to that shown in Figs. 4a to 4f but wherein the auxiliary yarns are disposed inwardly of the outside fabric edges according to a further practice of the invention, and illustrating also the formation of reinforced fabric by the use of main and splicing yarns with only one of such yarns forming the marginal loops;

Fig. 7a illustrates the initial step in a further widening operation following the last stage of the widening operation shown in Fig. 6f; and

Fig. 8 illustrates a section of fabric widened in a plurality of courses at the opposite margins according to the procedure illustrated in Figs. 6a to 6f and 7a, and showing the manner in which the auxiliary yarns are incorporated in the fabric.

In widening fabric by the addition of edge loops the traverse of the yarn carrier or carriers

which are reciprocated by the usual friction bar of the knitting machine is controlled by adjustable stops which are racked out during each widening operation so that yarn is laid to additional needles at the margin of the fabric. The idle carriers which feed the auxiliary yarn into the fabric according to the present invention remain idle except incident to the formation of widened courses as before mentioned, and are maintained at all times free of engagement with the friction rod so as not to be reciprocated thereby. Incident to widening, the idle carriers feeding the auxiliary yarn at the opposite margins of the fabric must be pulled out to a new position to the extent of the same number of needles, usually two, by which the width of the fabric is to be increased. For this purpose it is convenient to employ rebound lock mechanism such as used on machines for "ringless" knitting. Because such type mechanism locks the various yarn carriers of the machine in association with their end stops intermediate the completion of one course and the laying of the next course, the racking out of such devices on the opposite sides of the needle bar can serve not only to adjust the stops for the active carriers forming the fabric courses but also to pull out the idle carriers laying the auxiliary yarns at the margins of the fabric.

Referring now to the drawings, Figure 1 illustrates a single unit stocking blank knit on a flat machine comprising a top 60, leg portion 61, heel portions 62 and 62', foot portion 63 and toe portion 64 knit throughout as a unit and having continuous selvage edges at its opposite sides running from top to toe. The heel portions in their upper area W are progressively widened, thereafter a series of straight courses are knit in area Y, following which the lower heel portions are narrowed in area 4N. The blank is preferably further narrowed at the foot instep in area 2N. It is intended that the widening of the heel portions in the area W be accomplished through the addition of edge loops in selected courses, and according to the present invention auxiliary yarns will be employed incident to widening to guard against the formation of defective selvages such as might result in runs in the heel fabric.

It is contemplated under the invention to incorporate auxiliary yarns into the marginal widened areas of fabric either at the side edges thereof or at positions one or more needles inwardly of the side edges as both arrangements have been found to minimize the production of defective selvages. Assuming that the fabric is to be widened by two needles at each margin, the idle yarn carriers which feed the auxiliary yarn will always occupy positions over dividing sinkers when the auxiliary yarn is to be introduced into the fabric at the side edge or an even number of needles inwardly of the edge. Where the idle yarn is to be introduced into the fabric an odd number of needles inwardly from the edge the idle carriers which feed the same will be located in position over jack sinkers and under such circumstances either the jack sinkers must be cut down or special forms of idle carriers employed to prevent interference between the carriers and sinkers when the latter are projected during the knitting motion of the machine. When the auxiliary yarns are inset from the edges of the fabric they will preferably occupy positions not more than one or two needles inwardly, since it is not likely that they can serve any useful function incident to the formation of locked loops in the marginal

areas of the widened fabric portions if loaded further inwardly.

In Figure 2 is illustrated a section of fabric 1F having an initial width w^0 and widened in successive areas w^1 , w^2 and w^3 at its opposite margins. It is characteristic of widening by the addition of loops that the widening at the opposite margins occurs in different courses. For simplicity in Figure 1 it is assumed that the widening occurs in each instance at the left side in a later course than at the right side, although the reverse may be true, and in actual practice it is found desirable in one widening operation to widen first at the right and then at the left, and in the next widening operation to widen first at the left and then at the right, and so on alternately.

The idle carriers 1 and 2 feed auxiliary yarns 3 and 4 to the right and left marginal areas of the fabric. During the knitting of area w^0 the carriers 1 and 2 will occupy the respective positions 1P and 1P' so as to feed the yarns to the fabric along the opposite side edges thereof. When the fabric is widened in area w^1 , carriers 1 and 2 are moved out to positions 2P and 2P' with a consequent interknitting of yarns 3 and 4 with the added marginal loops of the fabric. When the fabric is again increased in the next widening operation in area w^2 following the knitting of any selected number of straight courses, carriers 1 and 2 will again move out to positions 3P and 3P', and in the following widening operation when the fabric is again increased in width in area w^3 , the carriers 1 and 2 will move out to positions 4P and 4P' in which they are represented in Figure 2. It will be understood that with each widening operation at each side of the fabric the idle carrier yarns 3 and 4 will be knit into the marginal areas of the fabric.

In Figure 3 is represented a section of widened fabric 2F similar to that shown in Figure 1, and again having an initial width w^0 followed by successive widened areas w^1 , w^2 and w^3 . Instead of being located at the side edges of the fabric the idle carriers 1 and 2 are located inwardly of the side edges of the fabric one or two needles so that the auxiliary yarns 3 and 4 are inset from the edges. During the knitting of area w^0 , carriers 1 and 2 will be located in positions 1PP and 1PP' and will be moved out to positions 2PP and 2PP' when the fabric is widened in area w^1 . The carriers move out to positions 3PP and 3PP' incident to the second widening in area w^2 , and when the fabric is again increased in width in area w^3 the idle carriers move out to positions 4PP and 4PP' in which they are shown.

The use of the auxiliary yarns according to Figure 2 is illustrated in its application to the method of widening by the addition of selvage loops of Somers Patent No. 2,230,986 in Figures 4a to 4f. It is assumed that the fabric is formed with the same yarn in successive courses, and in this case a single yarn 27 laid by the reciprocating yarn carrier 1C. The needles of the machine needle bank engaged in knitting the right marginal area of the fabric at the commencement of the widening are shown at x and o, and the corresponding needles at the left margin of the fabric are shown at x' and o'. The needles 1 and 2 are to be added at the right and needles 1' and 2' at the left in the widening operation. The dividing sinkers at the right and left are indicated at b and d and b' and d' and the jack sinkers at the right and left are respectively indicated at c and e and c' and e'. 75

Course II has been completed and yarn carrier 1C starting at the left lays course III to the right as shown in Figure 4a. With the needle bank up at the start of the laying of course III, the stops of carrier 1C at the opposite sides of the needle bank move out two needles so that at the right yarn 27 is extended across needles 1 and 2. After the sinkers are projected and the needles go down and up again to complete course 10 III, the yarn at the right then lying beneath dividing沉器 d but above jack沉器 e, carrier 1C moves to the left to lay course IV forming a loop p on dividing沉器 d between needles 1 and 2 at the right. Since the left stop of carrier 15 1C has already moved out yarn 27 is extended across needles 1' and 2' at the left in course IV, as shown in Figure 4b. When course IV is sunk and the needles move down for the knockover, at the right loop 32 is formed on needle 1 and the loop formed at p is drawn off dividing沉器 d and becomes loop 31, as shown in Figure 4c, which, as the needles rise again into course-laying position, is impaled on the outside added needle 2, as shown in Figure 4d. In the corresponding stages the yarn at the left in course IV is placed beneath dividing沉器 d' intermediate needles 1' and 2' and in laying course V from left to right, yarn 27 is formed into a loop on dividing沉器 d' at q. When the needles descend for the completion of course V, as shown in Figure 4e, loop 32' is formed on needle 1' and loop 31' formed on the divider at q is drawn off to a position adjacent needle 2' between the sinkers and knockover bits (not shown). When the needle bank again rises to course-laying position loop 31' is impaled on needle 2', as shown in Figure 4f.

At the start of the widening operation idle yarn carriers 3C and 4C, which respectively feed auxiliary yarns 23 and 24 to the fabric according to the invention will be located in the dotted line positions above dividers d and d' at the right and left, as shown in Figure 4a. When the stops for the course-laying yarn carrier 1C are racked out at the start of course III before the sinkers are projected, idle carrier 4C is moved out two needles at the left and carrier 3C at the right, with the result that the auxiliary yarn 24 is laid outwardly across needles 1' and 2' at the left and yarn 23 laid outwardly across needles 1 and 2 at the right. When the needles go down for the cast-off of course II and the completion of course III, auxiliary yarn 24 at the left is placed beneath divider d' and in the formation of course IV is interknit with the main yarn 27 at needle 1', as shown in Figure 4c. When course V is laid, as shown in Figure 4d, yarn 24 is encompassed with the loop of course yarn 27 formed on divider d' at q, and when such loop is drawn off the divider during the descent of the needles in completing course V, as shown in Figure 4e, and becomes loop 31', yarn 24 extends through such loop and serves to hold the same in position to be impaled on needle 2' when the needles again rise to the position shown in Figure 4f. In the operating stages just described it will be understood that the sequence of steps at the left margin of the fabric includes first the racking out of the idle auxiliary yarn carrier 4C incident to the laying of course III, the extension of the main yarn 27 at the left in course IV, and the completion of the widening at the left with the formation of locked loops 31' and 32' in course V.

At the right side of the fabric idle yarn carrier 3C is moved out incident to the laying of course

III, and the traverse of the yarn carrier 1C is also extended in this same course to lay yarn 27 across needles 1 and 2 as will be understood from Figure 4a. During the cast-off of course III and the completion of course IV auxiliary yarn 23 becomes interknitted with added loops 31 and 32 of the course yarn 27 and serves to aid in the impalement of loop 31 on needle 2, as will be understood from Figures 4c and 4d.

The fact that idle carriers 3C and 4C move out at the right and left in the same course (course III), whereas the added widening loops at the right and left occur in successive courses (courses IV and V), is merely a matter of expediency in machine operation, since it is found most convenient to rack out the active yarn carrier stops at the right and left simultaneously, and to rack out the right and left idle carriers at the same time through the same control mechanism. There is some reason to believe that the auxiliary yarn functions most effectively, at least in its application to the Somers method of widening, where the auxiliary yarn carrier at one side is moved out in the course preceding the course which is lengthened at that side, as illustrated in the widening at the left in Figures 4a to 4f. Thus, it may be considered desirable that idle carrier 3 at the right be racked out during the laying of course I instead of during the laying of course II.

Figure 5 illustrates the same fabric after further courses are knit and further widenings effected following completion of the first widening stage at the right and left shown in Figure 4f. Following the addition of added loops 31 and 32 in the right of course IV and added loops 31' and 32' at the left in course V, a further widening operation is effected, this time beginning at the left so that loops 33' and 34' are added at the left in course VII and loops 33 and 34 at the right in course VIII. In the next widening operation, the widening is again begun at the right to add loops 35 and 36 in course X and loops 35' and 36' at the left in course XI. Through alternating the side at which the widening operation is commenced, the auxiliary yarns are enabled to function to greatest advantage as explained just above in every other widening at the respective edges of the fabric where it is found convenient from the standpoint of machine operation to rack out the right and left idle carriers which feed the auxiliary yarns in the same courses.

In Figure 5 in the three widening operations six needles have been added at the right and six at the left to increase the width of the fabric by twelve wales, and of course the widening may be continued to any desired extent to obtain the required width of the heel sections 62 and 62' in Figure 1. Of course, any selected number of straight courses may be interposed between the courses in which the edge loops are added. It will be observed that the auxiliary yarns 23 and 24 are interknit incident to each widening operation, and because their respective carriers 3C and 4C are maintained along the outside edges of the fabric in the progressive stages of knitting, the auxiliary yarns become interknit with the outer added loops in all instances. The auxiliary yarns aid in the proper locking of the outer added loops as previously explained.

Assuming again that the fabric is widened two needles at the right and left sides, and that the same yarn is knit in successive courses, the auxiliary yarns may be fed to the marginal areas of the widened fabric inwardly of the side edges, as

illustrated in Figures 6a to 6f. In this case the fabric is knit throughout portions of its width with a plurality of yarns for purposes of reinforcement such as is desirable in the heel sections 5 of the stocking blank shown in Figure 1. In 10 knitting widened reinforced fabric it is found desirable in insuring against the formation of defective stitches again to incorporate the auxiliary yarns. As a further feature, it is proposed to 15 terminate the reinforcement inwardly of the side edges. This last can be done when the auxiliary 20 yarn is fed along the side edges as in the practice of the invention described in connection with Figures 4a to 4f, but will be made sufficiently clear 25 in connection with the practice of the invention shown in Figures 6a to 6f where the auxiliary 30 yarns are fed inwardly of the edges.

The fabric in Figure 6a is formed not only by 35 yarn 27 fed by carrier 1C, but for portions of its courses at the right and left by yarn 21 fed by carrier 1C and yarn 22 fed by carrier 2C. Instead of stopping carriers 1C and 1C at the right at the same needle, one of such carriers, in this case the splicing yarn carrier 1C, has a 40 stop position beyond the other so that the marginal wales, preferably not more than two, will comprise only one of the yarns, whereas the next inward wales comprise doubled loops comprising both such yarns. The same condition 45 is effected at the left side of the fabric, splicing yarn carrier 2C having an end position outwardly of the left end position of carrier 1C.

In Figure 6a straight courses 1 and 2 have 50 been knit preparatory to widening. During the knitting of such courses splicing carrier 1C will stop at a right end position over dividing sinker d and carrier 1C will have a more inwardly right end stop position over dividing sinker b, and at the left splicing yarn carrier 2C will have a 55 left end position over dividing sinker d' and carrier 1C will have a more inwardly left end position over dividing sinker b'. Stops for splicing 60 yarn carriers 1C and 2C at the inner ends of their traverse will be adjusted to positions determined by the width of reinforcement desired in the fabric. It will be observed that the wales on needles x and o at the right are composed solely of the splicing yarn 21 while the next inner loops are formed double of splicing and 65 main yarns 21 and 27. Similarly at the left the two marginal loops on needles o' and x' are formed solely of splicing yarn 22 whereas the next inner loops are formed double of splicing and 70 yarns 22 and 27.

Following the completion of course II with the needles in up position the carrier stops are moved out for the start of a widening operation preparatory to laying course III to the right. With the laying of such course as shown in Figure 6a carrier 1C lays the yarn 21 across additional needles 1 and 2 while carrier 1C extends yarn 27 across needles x and o. Upon the completion of course III course IV is laid to the left with the formation of a loop of yarn 21 on dividing sinker d at point r. When the needles go down to cast off course III loop 52 is formed on needle 1 and loop 51 which was formed on the sinker is placed below the line of sinkers adjacent needle 2, and is impaled on needle 2 when the needles rise again for the laying of course V as shown in Figure 6d.

In the laying of course IV to the left, as shown in Figure 6b, carrier 2C lays splicing yarn 22 across additional needles 1' and 2' while the traverse of carrier 1C is extended to lay yarn

27 across needles x' and o' . Following the completion of course IV and with the laying of course V, as shown in Figure 6d, yarn 22 is formed into a loop around dividing sinker d' at point s, and when the needles go down loop 52' is formed on needle 1' and the sinker-formed loop becomes loop 51' occupying a position below the line of sinkers as shown in Figure 6e preparatory to being impaled on needle 2' when the needles rise again as shown in Figure 7 preparatory to the laying of course VI.

At the completion of course II prior to the start of widening, the idle carrier 4C occupies a position over dividing sinker b' so as to feed auxiliary yarn to the marginal fabric areas but inside the marginal loops formed on needles x' and o' . At the start of laying course III to the right, the outside stops at the right and left for the splicing and main yarn carriers 1C, 2C and 1C are moved out two needles, and simultaneously therewith the right and left idle carriers 3C and 4C are moved out two needles to respective positions over dividing sinkers d and d' as shown in Figure 6a. At the left auxiliary yarn 24 is thus laid outwardly across needles x' and o' while yarn 22 is laid inwardly across such two needles by carrier 2C. When the needles go down to cast off course II following projection of the sinkers, double loops of the auxiliary yarn 24 and splicing yarn 22 are formed on needles x' and o' . At the right loops comprising the auxiliary yarn 23, and main and splicing yarns 27 and 21 are formed on needles o and x , as shown in Figure 6b.

By referring to the further widening stages illustrated in Figures 6e and 6f, and by collaterally referring to Figure 3, it will be observed that the auxiliary yarns 23 and 24 are not interknit with the added loops 51, 52 and 51', 52', since in the course of the first widening operation the auxiliary yarns are not fed across the added needles 1, 2 and 1', 2', but only across the old marginal needles x , o , and x' , o' . However, at the start of the second widening operation illustrated in Figure 7a the idle carriers are moved out across needles 1, 2 and 1', 2' and form loops thereon in course VI, as will be understood from Figure 8, preparatory to the adding of loops 54' and 53' on needles 3' and 4' at the left and the adding of loops 54 and 53 on needles 3 and 4 in course VIII at the right. Hence, even though the machine has failed to add loops of splicing yarns 22 and 21 respectively in courses IV and V, the formation of loops of auxiliary yarn 24 on needles 1' and 2' at the left, and of auxiliary yarn 23 on needles 1 and 2 at the right, will facilitate the delayed addition of locked loops of the splicing yarns on these needles.

Figure 8 shows the section of fabric in a further operating stage after the completion of three widening operations. As in the case of Figure 5 in the first widening operation loops are added at the right and then at the left, and in the second operation first at the left and then at the right, and in the third widening operation first at the right and then at the left, which alternate procedure is preferably carried on throughout the entire widened area of the fabric for reasons previously explained. At the left it will be observed that the auxiliary yarn 24 is knit in courses III, VI and IX, and that the loops of splicing yarn 22 are added in courses V, VII and XI. At the right the auxiliary yarn 23 is knit into the same courses as auxiliary yarn 24 at the

75 left, and loops of splicing yarn 21 are added at the right in courses IV, VIII and IX.

The margin loops of the fabric in which the auxiliary yarns enter at the right and the left in course III are respectively indicated at 41, 42, and 41', 42' in Figures 6c to 6f, 7a and 8. These are formed on the marginal needles o , x , and x' , o' , rather than on the added needles. However, the auxiliary yarns enter into loops 43, 44 at the right and 43', 44' at the left of course VI on the needles 1, 2, and 1', 2' over which the course-forming yarns, here splicing yarns 21 and 22, were extended in the first widening operation at the opposite sides. The loops in which the auxiliary yarns enter in the third widening operation at the right and left of course IX are indicated at 45, 46 and 45', 46', respectively, these being formed on needles 3, 4 and 3', 4' over which the course-forming yarns were extended in the second widening operation as indicated by loops 53, 54, and 53', 54'. In the fourth widening (not shown) loops of the auxiliary yarns will be formed on needles 5, 6, and 5', 6' to which the course-forming yarns were extended, as represented by loops 55, 56, and 55', 56', in the third widening.

It has been found in practice that improved selvages are obtained in widened fabric with the assistance of the auxiliary yarns both when such yarns are fed at the edge of the fabric and when fed inwardly of the fabric edge according to the several procedures herein described. It will be obvious, of course, that the practices of the invention herein described and shown are merely illustrative and that the inventive process may be carried out in a variety of ways within the scope of the appended claims, with reference to the position of the auxiliary yarn relative to the fabric margin in any case, and with reference to the positions of the auxiliary yarn, body yarn and splicing yarn relative to each other and to the fabric margin in the case of reinforced fabric, and depending on whether the adding of loops to widen the fabric courses is carried out according to the Somers method or some other procedure.

The invention will be understood to have particular utility in forming widened heel sections in single unit stockings, but of course can be used for other purposes.

We claim:

1. The method of adding selvage loops to widen fabric on a flat knitting machine which includes increasing the traverse of the reciprocating course-forming yarn carrier or carriers in selected fabric courses across additional needles beyond the edge of the fabric marginal area for the formation of loops on said additional needles, feeding an auxiliary yarn to the fabric marginal area lengthwise of said edge from a stationary yarn carrier positioned near said additional needles, and shifting the position of the auxiliary yarn carrier outwardly a corresponding number of needles for each widening.

2. The method of adding selvage loops to widen fabric on a flat knitting machine which includes increasing the traverse of the reciprocating course-forming yarn carrier or carriers in selected fabric courses across additional needles beyond the edge of the fabric marginal area for the formation of loops on said additional needles, feeding an auxiliary yarn to the fabric marginal area lengthwise of said edge from a stationary yarn carrier positioned near said addi-

same additional needles for each widening at said edge.

13. The method of adding selavage loops to widen fabric on a flat knitting machine which includes increasing the traverse of the reciprocating course-forming yarn carrier or carriers in selected fabric courses across additional needles beyond the edge of the fabric marginal area for the formation of loops on said additional needles, feeding an auxiliary yarn to the fabric from a stationary yarn carrier positioned at said edge of the fabric marginal area, and shifting the position of the auxiliary yarn carrier outwardly to lay the auxiliary yarn across the beard side of the same additional needles for each widening at said edge.

14. The method of adding selavage loops to widen fabric on a flat knitting machine which includes increasing the traverse of the reciprocating course-forming yarn carrier or carriers in selected fabric courses across additional needles beyond the edge of the fabric marginal area for the formation of loops on said additional needles, feeding an auxiliary yarn to the fabric from a stationary yarn carrier positioned in the marginal area inwardly of said edge, and shifting the position of the auxiliary yarn carrier outwardly to lay the auxiliary yarn across the beard side of the same additional needles in a course subsequent to the course in which the reciprocating yarn carrier traverse is increased across said additional needles at said edge.

15. The method of adding selavage loops to widen fabric on a flat knitting machine which includes increasing the traverse of the reciprocating course-forming yarn carrier or carriers in selected fabric courses across two additional needles beyond the edge of the fabric marginal area for the formation of loops on said additional needles, feeding an auxiliary yarn from a stationary yarn carrier to the fabric marginal area lengthwise of said edge, and shifting the position of the auxiliary yarn carrier outwardly two needles for each widening at said edge.

16. The method of adding selavage loops to widen fabric on a flat knitting machine which includes increasing the traverse of the reciprocating course-forming yarn carrier or carriers in selected fabric courses across two additional needles beyond the edge of the fabric marginal area for the formation of loops on said additional needles, feeding an auxiliary yarn to the fabric from a stationary yarn carrier positioned at the edge of the fabric marginal area, and shifting the position of the auxiliary yarn carrier outwardly two needles to lay the auxiliary yarn across the beard side of the same additional needles for each widening at said edge.

17. The method of adding selavage loops to widen fabric on a flat knitting machine which includes increasing the traverse of the reciprocating course-forming yarn carrier or carriers in selected fabric courses across two additional needles beyond the edge of the fabric marginal area for the formation of loops on said additional needles, feeding an auxiliary yarn to the fabric from a stationary yarn carrier positioned in the marginal area inwardly of said edge, and shifting the position of the auxiliary yarn carrier outwardly two needles to lay the auxiliary yarn across the beard side of the same two additional needles in a course subsequent to the course in which the reciprocating yarn carrier traverse is increased across said two additional needles at said edge.

18. The method of adding selavage loops to widen fabric at both sides on a flat knitting machine which includes increasing the traverse of the reciprocating course-laying yarn carrier or carriers in selected fabric courses across additional needles beyond one fabric marginal area, and in the next courses across additional needles beyond the opposite fabric marginal area, for the formation of loops on the additional needles, feeding auxiliary yarns to the fabric from stationary yarn carriers positioned at the edges of the opposite marginal areas, and shifting the positions of the respective auxiliary yarn carriers outwardly to lay yarn across the beard side of the same additional needles at the opposite marginal areas over which the reciprocating yarn carrier traverse is increased.

19. The method of adding selavage loops to widen fabric at both sides on a flat knitting machine which includes increasing the traverse of the reciprocating course-laying yarn carrier or carriers in selected fabric courses across additional needles beyond one fabric marginal area, and in the next courses across additional needles beyond the opposite fabric marginal area, for the formation of loops on the additional needles, feeding auxiliary yarns to the fabric from stationary yarn carriers positioned in the opposite marginal areas inwardly of their edges, and shifting the positions of the respective auxiliary yarn carriers outwardly to lay yarn across the beard side of the same additional needles at the opposite marginal areas over which the reciprocating yarn carrier traverse is increased but subsequent to the courses in which the course-forming yarn is extended across said additional needles at the opposite marginal areas.

20. The method of adding selavage loops to widen fabric on a flat knitting machine as in claim 18, wherein the positions of the respective auxiliary yarn carriers at the opposite marginal areas are shifted simultaneously in a common course.

21. The method of adding selavage loops to widen fabric on a flat knitting machine as in claim 19, wherein the positions of the respective auxiliary yarn carriers at the opposite marginal areas are shifted simultaneously in a common course subsequent to the successive courses in which the reciprocating yarn carrier traverse is increased across the additional needles at the opposite edges.

22. The method of adding selavage loops to widen fabric on a flat knitting machine which includes feeding an auxiliary yarn to the fabric from a stationary yarn carrier positioned at the fabric marginal area during formation of the fabric courses of yarn laid by one or more reciprocating yarn carriers, increasing the reciprocating yarn carrier traverse periodically in selected courses, laid in the direction of said marginal area, while the needle bar is up in course-laying position to extend the course-forming yarn across the beard side of two additional needles beyond said marginal area, and with the course-forming yarn still on the beard side of the two additional needles after the needle bar goes down to knockover and back up laying a second course in the opposite direction across the needle bar and forming the second course into knitted loops when the needle bar again goes down to knockover and back up, and for each widening operation at said marginal area shifting the position of the auxiliary yarn carrier outwardly while the needle bar is up in course-

laying position to lay the auxiliary yarn across the beard side of two needles at the marginal area.

23. The method of adding selavage loops to widen fabric on a flat knitting machine wherein successive fabric courses are formed of the same yarn laid by one or more reciprocating yarn carriers, which includes feeding an auxiliary yarn to the fabric from a stationary yarn carrier positioned at the fabric marginal area during formation of the fabric courses, increasing the reciprocating yarn carrier traverse periodically in selected courses, laid in the direction of said marginal area, while the needle bar is up in course-laying position to extend the course-forming yarn across the beard side of two additional needles beyond said marginal area, and with the course-forming yarn still on the beard side of the two additional needles after the needle bar goes down to knockover and back up laying a second course in the opposite direction across the needle bar and forming the second course into knitted loops when the needle bar again goes down to knockover and back up, and for each widening operation at said marginal area shifting the position of the auxiliary yarn carrier outwardly while the needle bar is up in course-laying position to lay the auxiliary yarn across the beard side of two needles at the marginal area.

24. The method of adding selavage loops to widen fabric on a flat knitting machine wherein successive fabric courses are formed of the same yarn laid by one or more reciprocating yarn carriers, which includes feeding an auxiliary yarn along the outside of the edge needle of the marginal area from a stationary yarn carrier during formation of the fabric courses, increasing the reciprocating yarn carrier traverse periodically in selected courses, laid in the direction of said marginal area, while the needle bar is up in course-laying position to extend the course-forming yarn across the beard side of two additional needles beyond said marginal area, and with the course-forming yarn still on the beard side of the two additional needles after the needle bar goes down to knockover and back up laying a second course in the opposite direction across the needle bar and forming the second course into knitted loops when the needle bar again goes down to knockover and back up, and for each widening operation at said marginal area shifting the position of the auxiliary yarn carrier outwardly two needles while the needle bar is up in course-laying position to lay the auxiliary yarn across the beard side of the same two additional needles to which the course-forming yarn is extended.

25. The method of adding selavage loops to widen fabric on a flat knitting machine wherein successive fabric courses are formed of the same yarn laid by one or more reciprocating yarn carriers, which includes feeding an auxiliary yarn to the fabric marginal area inwardly of the two edge needles of the marginal area from a stationary yarn carrier during formation of the fabric courses, increasing the reciprocating yarn carrier traverse periodically in selected courses, laid in the direction of said marginal area, while the needle bar is up in course-laying position to extend the course-forming yarn across the beard side of two additional needles beyond said marginal area, and with the course-forming yarn still on the beard side of the two additional needles after the needle bar goes down to knock-

over and back up laying a second course in the opposite direction across the needle bar and forming the second course into knitted loops when the needle bar again goes down to knockover and back up, and for each widening operation at said marginal area shifting the position of the auxiliary yarn carrier outwardly two needles while the needle bar is up in course-laying position to lay the auxiliary yarn across the beard side of the two edge needles of the marginal area, and in a course subsequent to the course in which the course-forming yarn is extended across the two additional needles beyond the marginal needles again shifting the position of the auxiliary yarn carrier outwardly two needles while the needle bar is up in course-laying position to lay the auxiliary yarn across the beard side of the said two additional needles across which the course-forming yarn is extended.

26. The method of adding selavage loops to widen fabric at both sides which includes feeding auxiliary yarns from stationary yarn carriers to the respective opposite fabric marginal areas during formation of the fabric courses of yarn laid by one or more reciprocating yarn carriers, effecting a first widening at the opposite sides of the fabric by increasing the reciprocating yarn carrier traverse in a selected course, laid in the direction of one marginal area, while the needles are up in course-laying position to extend the course-forming yarn across the beard side of additional needles beyond the first marginal area, shifting the positions of the auxiliary yarn carriers at both marginal areas outwardly during extension of said first course to place the auxiliary yarns across the beard side of a corresponding number of needles at both marginal areas, increasing the reciprocating yarn carrier traverse in the following second course, laid in the direction of the second marginal area, while the needles are up in course-laying position to extend the course-forming yarn across the beard side of additional needles beyond the second marginal area, forming a third course, laid in the direction of the first marginal area, across the additional needles beyond both marginal areas, effecting a second widening at the opposite sides of the fabric by increasing the reciprocating yarn carrier traverse first in a course subsequent to the second course, laid in the direction of the second marginal area, while the needles are up in course-laying position to extend the course-forming yarn across the beard side of further additional needles beyond the second marginal area, shifting the positions of the auxiliary yarn carriers at both marginal areas outwardly during extension of said subsequent course at the second marginal area to place the auxiliary yarns across the beard side of a corresponding number of needles at both marginal areas, then increasing the reciprocating yarn carrier traverse in the next course following said subsequent course, laid in the direction of the first marginal area, while the needles are up in course-laying position to extend the course-forming yarn across the beard side of further additional needles beyond the first marginal area, and after forming said last-mentioned course extended at the first marginal area forming another course, laid in the direction of the second marginal area, across the further additional needles beyond both marginal areas.

27. The method of adding selavage edges to widen reinforced fabric on a flat knitting ma-

chine wherein the fabric courses are formed of a body yarn and a splicing yarn laid by separate reciprocating yarn carriers, which includes adjusting the traverse of the respective reciprocating yarn carriers feeding the body yarn and the splicing yarn so that in the fabric marginal area one of said carriers feeds its yarn to outer marginal needles not fed by the other carrier for the formation on said marginal needles in the fabric courses of loops composed of only one of said yarns, feeding auxiliary yarn at the edge of the marginal area outside said outer marginal needles from a stationary yarn carrier during formation of the fabric courses, periodically increasing the traverse of the course-laying yarn carriers in selected courses and extending the yarn feeding said outer marginal needles across additional needles beyond said outer marginal needles for the formation of loops thereon, and for each widening at said marginal area shifting the auxiliary yarn carrier outwardly to extend the auxiliary yarn across said additional needles.

28. The method of adding selvage edges to widen reinforced fabric on a flat knitting machine wherein the fabric courses are formed of a body yarn and a splicing yarn laid by separate reciprocating yarn carriers, which includes adjusting the traverse of the respective reciprocating yarn carriers feeding the body yarn and the splicing yarn so that in the fabric marginal area one of said carriers feeds its yarn to outer marginal needles not fed by the other carrier for the formation on said marginal needles in the fabric courses of loops composed of only one of said yarns, feeding auxiliary yarn from a stationary yarn carrier to the marginal area inwardly of at least some of said outer marginal needles fed by only one of said course-forming

yarns during formation of the fabric courses, periodically increasing the traverse of the course-forming yarn carriers and extending the yarn feeding said outer marginal needles across additional needles beyond said outer marginal needles for the formation of loops thereon, and for each widening at said marginal area shifting the auxiliary yarn carrier outwardly to extend the auxiliary yarn across said outer marginal needles, and shifting the auxiliary yarn carrier outwardly in a subsequent widening to extend the auxiliary yarn across the additional needles beyond the outer marginal needles to which the one course-forming yarn is extended in the preceding widening.

29. The method of producing selvage-edged widened heel sections at the opposite sides of a stocking blank knit as a single unit on a flat knitting machine of the full-fashioned hosiery legger type through the addition of selvage loops at the opposite marginal areas of the blank, and wherein successive heel courses are formed of yarn laid by the same reciprocating yarn carriers, which includes feeding auxiliary yarns to the opposite marginal areas of the blank during formation of the heel courses, periodically widening the blank by increasing the reciprocating yarn carrier traverse in selected heel courses at the respective sides of the blank to extend the course-forming yarn across additional needles beyond the marginal areas of the heel sections for the formation of loops thereon, and for each widening at the respective sides shifting the auxiliary yarn carriers feeding to the marginal areas of the opposite heel sections outwardly a corresponding number of needles.
